CLAIM

The ornamental design for a pad holder for polishing apparatus, as shown and described.

DESCRIPTION

FIG. 1 is a first perspective view, observed from top of a pad holder for polishing apparatus showing our new design; FIG. 2 is a second perspective view, observed from bottom thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.
